UNITED STATES PATENT OFFICE

GIOVANNI PASSEFIUME, OF PORTLAND, OREGON

SHOE SOLE CHANNELING MACHINE

Application filed February 10, 1930. Serial No. 427,217.

My invention relates to the manufacture and repair of shoes and the like and particularly to repair and has for its particular object the provision of an inexpensive, simple 5 machine for producing a side or channel cut in the edge portions of the shoe soles.

That is, in stitching soles to the welt, it is desirable that the stitching be concealed beneath the wearing surface and for this reason 10 a thin section of the sole adjacent such wearing surface is cut away from the remainder of the sole at its outer edge and bent upwardly about its inner edge. The stitching operation is then completed and the channel portion 15 is returned to its original position and is cemented in place and when cemented provides an effective covering strip for the stitching, which would otherwise show.

For the reason that the marginal edge is 20 cemented down, it is preferable to make it quite thin to interpose the least possible surface for engagement and for rupturing such cemented joint. To this end, a more particular object of my invention is to provide a 25 bench tool of this character which can be fastened in place and in which the parts are arranged to be operated efficiently and with substantial accuracy, and in which the parts are arranged to permit efficient operation of 30 such tool.

These features of my invention are herein-after described in greater detail and with reference to the accompanying drawings, in which:

35 Fig. 1 is a side elevation of such tool;

Fig. 2 is a front elevation taken in the direction of the arrow 2 in Fig. 1; and

Fig. 3 is a plan view thereof.

40 My improved channeling machine comprises a base having an upstanding flange portion *b* at its upper end and the broad-faced seat *b'* at the opposite end, which seat serves as a fastening means to a bench or other support. Such base is preferably fastened 45 to such bench or other support by screws *b2* which pass thru such portion *b'*. Pivottally mounted upon such flange portion *b* is a head *c*, one end of which is bifurcated as at *c'*. A pivot pin *d* constitutes the fastening 50 means between such flange and such head and is of sufficient size to provide a strong bearing. The top portion of the base, and head *c* define the work-receiving throat and said head is preferably spread away from the base by a coil spring mounting *f* with which 55 engages a centered pin or pins *f'*. The free end of head *c* is perforated at *c2* to constitute a means of fastening with a chain or cable for distant control, such for example as a foot-operated treadle, so as to leave both 60 of the operator's hands free to guide the work and operate the feeding means. Carried by the head is a serrated roller *g* keyed, or otherwise fixed, to a driving shaft *h* journaled in the head at *h2*, as shown in Fig. 2, and 65 driven by a handle *h3*. Arranged in cooperative alignment with the serrated roller *g* is a tapered roller *i* mounted for free rotation on the base. Mounted adjacent the roller *i* are work-positioning guides *j'* and *k*. 70 The guide *j'* is preferably arranged at the inlet side of the roller *i* and is a vertical guide, the inner marginal edge conforming generally to the periphery of the tapered roller *i*. Such guide *j'* is preferably angular 75 in form and extends around one corner of the base and is fastened by two screws *j2*, which pass thru slotted holes in such guide. Such slotted holes permit lateral adjustment of such guide with respect to the tapered roller. 80 The guide *k* is provided with a horizontal surface *k'*, which extends laterally out from the base, and the inner marginal surface of such guide also conforms generally to the periphery of the tapered roller and two 85 threaded screw connections *k2* also fasten this guide to the base. The guides *j'* and *k* are thus mounted so as to be adjustable to meet the conditions encountered in the work. A 90 knife blade member *m* having a forwardly arranged cutting edge *m'* extends laterally of the frame and lies in the work-receiving throat, being recessed in a laterally arranged slot in such base and fastened in place by a screw connection 1. 95

As is shown in Fig. 2, considered with respect to its longest dimension and laterally of the machine, the blade *m* is arranged angularly with respect to the periphery of the roller *i*. This is for the reason that it is de- 100

sirable to make such channel cut of progressively increased depth away from the marginal edge of the shoe sole to make a so-called "feather edge" cut. A "feather edge" cut 5 is one where the outer portion of such material thus severed from the remainder of the sole is of negligible thickness and the remainder thereof is progressively increased in thickness, so that the portion of such severed strip which remains connected to the 10 sole is of substantial thickness, so as not to be readily torn therefrom. Much difficulty has been experienced heretofore in producing an accurate cut of this description without the 15 use of a heavy piece of machinery and as all previous attempts to effect this cut with which I am familiar have been done by arranging the blade at the proper angle to the base, I have reversed such elements with 20 unusually good results—that is, by arranging the knife blade in a plane parallel to the horizontal guides and arranging the surface of the roller at an oblique angle with respect thereto, the taper being computed to give 25 the desired difference in thickness in such channel cut strip.

I claim:

1. A shoe sole channeling machine comprising a base provided with an upstanding 30 mounting, a head pivotally secured to the latter, defining a throat with the upper portion of said base, a pair of cooperating feed rollers carried by said head and said base respectively, positive means for driving one of said 35 rollers, the periphery of one of said rollers being tapered to a predetermined degree and a knife element mounted in such throat in fixed horizontal relation to said last mentioned roller, said knife element being mounted 40 in a close-fitting slot in said throat engaging the edges of said knife.
2. A shoe sole channeling machine comprising a base provided with an upstanding mounting, a head pivotally secured to the 45 latter, defining a throat with the upper portion of said base, a pair of cooperating feed rollers carried by said head and said base respectively, positive means for driving one of said rollers, resilient means normally spacing 50 the head from said body and therewith said rollers, manually adjustable, distant control means opposing said resilient means, the periphery of one of said rollers being tapered to a predetermined degree and a knife 55 element mounted in such throat in fixed horizontal relation to said last mentioned roller, said knife element being mounted in a close-fitting slot in said throat engaging the edges of said knife, and a guiding surface under- 60 lying said knife element, in substantially parallelism therewith and in adjustable relation to said tapered roller.

In testimony whereof he has affixed his signature.
